(57) CLAIM

The ornamental design for a shoe upper, as shown and described.

DESCRIPTION

FIG. 1 is a perspective view of a shoe upper;

FIG. 2 is a lateral side view of the shoe upper;

FIG. 3 is a medial side view of the shoe upper;

FIG. 4 is a front view of the shoe upper;

FIG. 5 is a rear view of the shoe upper; and,

FIG. 6 is a top view of the shoe upper.

A shoe upper is shown in FIGS. 1-6. Dashed lines have been included for illustrative purposes only, and form no part of the claimed design.
